UNITED STATES PATENT OFFICE.

AUSTIN GILBERT AND CHARLES E. VANDER HOOF, OF HAMILTON, OHIO, ASSIGNORS TO
THE FISCHER CAN COMPANY, OF HAMILTON, OHIO.

SEALING COMPOSITION FOR CANS.

1,323,752.

Specification of Letters Patent.

Patented Dec. 2, 1919.

No Drawing.

Application filed July 2, 1919. Serial No. 308,188.

To all whom it may concern:

Be it known that we, AUSTIN GILBERT and CHARLES E. VANDER HOOF, citizens of the United States, residing at Hamilton, Butler 5 county, Ohio, have invented certain new and useful Improvements in Sealing Compositions for Cans, of which the following is a specification.

This invention, pertaining to the sealing 10 of cans, relates to a composition to be employed in the sealing of the lids of the cans to place.

Our sealing composition consists of:—

Crude rubber	-----	6 pounds.
Benzol	-----	About 38 gallons.
Beeswax	-----	About 2 pounds.
Paraffin wax	-----	About 2 pounds.
Talcum powder	-----	About 7 pounds.

20 This composition we apply to the portion

of the lid which is to make contact with the flange of the can body. The evaporation of the benzol leaves a substantially dry coating, leaving the lid in condition for future application to the can-body. When the lid 25 is applied to the can-body then the skirting is forcibly turned up under the flange, causing the composition to be compressed between the lid and the flange of the can-body.

30 We claim:—

A sealing composition for cans consisting of crude rubber, benzol, beeswax, paraffin wax, and talcum powder, in the proportions combined substantially as set forth.

AUSTIN GILBERT.
CHARLES E. VANDER HOOF.
